(57) **CLAIM**

The ornamental design for a medical basin, as shown and described.

DESCRIPTION

FIG. 1 is a front perspective view of a first embodiment of a medical basin according to the present invention.

FIG. 2 is a front elevation view of the medical basin illustrated in FIG. 1.

FIG. 3 is a rear elevation view of the medical basin illustrated in FIG. 1.

FIG. 4 is a side elevation view of the medical basin illustrated in FIG. 1.

FIG. 5 is another side elevation view of the medical basin illustrated in FIG. 1.

FIG. 6 is a top plan view of the medical basin illustrated in FIG. 1.

FIG. 7 is a bottom plan view of the medical basin illustrated in FIG. 1.

FIG. 8 is a front perspective view of a second embodiment of a medical basin according to the present invention.

FIG. 9 is a front elevation view of the medical basin illustrated in FIG. 3.

FIG. 10 is a rear elevation view of the medical basin illustrated in FIG. 8.

FIG. 11 is a side elevation view of the medical basin illustrated in FIG. 8.

FIG. 12 is another side elevation view of the medical basin illustrated in FIG. 8.

FIG. 13 is a top plan view of the medical basin illustrated in FIG. 8.

FIG. 14 is a bottom plan view of the medical basin illustrated in FIG. 8.

FIG. 15 is a front perspective view of a third embodiment of a medical basin according to the present invention.

FIG. 16 is a front elevation view of the medical basin illustrated in FIG. 15.

(Continued)

FIG. 17 is a rear elevation view of the medical basin illustrated in FIG. 15.

FIG. 18 is a side elevation view of the medical basin illustrated in FIG. 15.

FIG. 19 is another side elevation view of the medical basin illustrated in FIG. 15.

FIG. 20 is a top plan view of the medical basin illustrated in FIG. 15; and,

FIG. 21 is a bottom plan view of the medical basin illustrated in FIG. 15.
